UNITED STATES PATENT OFFICE.

CHARLES D. CURRY, OF HENRYETTA, OKLAHOMA.

RAIL TIE.

Application filed May 19, 1926. Serial No. 110,291.

The object of this invention is the provision of a metallic tie for railway rails, and means for securing the rails thereon.

A further object is the provision of a metallic tie of such construction that the same will be held from lateral or longitudinal movement when arranged in the road bed and which has means associated therewith for effectively securing the rails thereon 10 in an easy and expeditious manner.

A further object is the provision of a metallic tie for railway rails having cushioning plates on which the rails rest so that the rails are afforded desired resiliency, together with clamping means, of a novel nature for securing the rails on the tie, said means being adjustable both vertically and longitudinally, the former adjustment compensating for any wear that may be occasioned upon the cushioning plates and the latter adjustment insuring the firm gripping engagement of the clamps with the rails.

To the attainment of the foregoing the invention consists in the improvement as hereininafter described and definitely claimed.

In the drawings:

Figure 1 is a side elevation of a tie having rails clamped thereon in accordance with this invention.

Figure 2 is a top plan view on an enlarged scale looking toward one of the ends of the tie, the rails being in section.

Figure 3 is an approximately sectional view on the line 3—3 of Figure 2.

Figure 4 is a plan view of the portion of the tie illustrated in Figures 2 and 3, with the rail and the clamping means therefor removed.

Figure 5 is a sectional view on the line 40 5—5 of Figure 4.

Figure 6 is a perspective view of one of the cushioning plates.

Figure 7 is a similar view of one of the rail clamps.

Figure 8 is a fragmentary bottom plan view of the tie.

As disclosed by the drawings, the tie 1 is of a desired length and width. The tie is of metal, and has on its under face, its edge 50 and ends formed with a continuous downwardly directed preferably V-shaped flange 2. Intersecting cross sectionally V-shaped ribs 3 are also integrally formed on the bottom of the tie and merge into the side ribs 2.

The tie, on its top, at a suitable distance 55 from its ends, is provided with transverse

depressions 21, and these depressions afford seats for the base flanges 10 of rails 11. The edges of the base flanges of the rails contact with the side walls provided by the rail 60 seats 21. The ties, at the center thereof, are grooved longitudinally, the said grooves extending in opposite directions from the ends of the rail seats 21. The outer grooves are indicated by the numerals 4 and the inner 65 grooves by the numerals 5. The grooves 4 communicate with the ends of the tie. Formed on the side walls provided by the grooves 4 and 5, at suitable points away from the ends of the said grooves, there are 70 formed longitudinally extending lugs 6. These lugs with the grooves, provide the top of the tie with substantially T-shaped slots and the spaces between the lugs 6 which provide the restricted passages of the said 75 T-shaped slots are indicated for distinction by the numerals 17. The upper face of the tie from the side walls provided by the rail seats 21 is formed with longitudinal depressions whose bottoms 8 are inclined 80 downwardly toward the said rail seats 21 and whose side walls 9 are straight and are arranged in parallelism. The passages 17 are directed centrally through the bottoms 8 of the depressions.

The rail clamps 12 are designed to be received in the depressions 8 and are of a width to snugly contact the side walls or shoulders 9 thereof, and the said rail clamps have their under faces thickened adjacent to the 90 end edges thereof, and from thence beveled in opposite directions, as indicated by the numerals 13 and 14, respectively. Each rail clamp 12 has a bolt opening 15 therethrough, and the openings are designed to receive 95 therethrough the shanks of headed bolts 16, the heads of the bolts being received in the grooves 4 and the shanks passing through the restricted passage 17 provided between the confronting edges of the oppositely disposed pairs of lugs 6. The bolts, of course, are engaged by nuts 18, and these nuts compress lock washers 19 against the clamps 12.

Before the clamps are brought into rail engagement there is arranged in each of the 105 rail seats 21 a cushioning plate 20. The cushioning plate affords the rails practically the same resiliency as is afforded by a wooden tie and any wear on the cushioning plates can be taken up by screwing the 110 nuts 18 home on the bolts. The outer beveled faces 12 of the clamps rest on the in-

clined walls 8 so that a firm engagement is sustained between these portions of the construction which will prevent any liability of outward movement or a movement of the 5 clamps away from rail engagement. By providing the bottom of the tie with the ribs it will be apparent that when the same is arranged in the road bed the said tie will 10 bitingly engage therewith and thus be prevented from either lateral or longitudinal movement.

While I have illustrated a satisfactory embodiment of my improved device my features of invention are capable of extended 15 application and I do not wish to be limited to the specific structure herein shown and described.

Having described the invention, I claim:—

20 1. A metal tie for railway rails, impinging flanges in the lower face thereof, said tie having its upper face at points adjacent its ends, formed with aligning grooves, outstanding lugs at the opposite sides of the 25 grooves and having their inner edges partly covering said grooves, the space between the grooves designed to provide a rest for railway rails, clamps disposed over the lugs, bolt members having their heads let in the 30 grooves and their shanks passing between the lugs and through the clamps, and nuts screwed on the clamps for holding the latter in rail engagement.

35 2. A metal tie for railway rails having its upper face and at points inward of its ends provided with aligning pairs of

grooves, lugs integrally formed on the top of the tie at the opposite sides of the grooves and having their inner edges partly overlying said grooves, a cushioning plate arranged between the grooves of each pair and providing a seat for railway rails, clamps seated on the lugs for engagement with the base flanges of the rails, bolts having their heads received in the grooves, their 45 shanks passing between the lugs and through the clamps, and nuts threaded on said bolts.

3. A metal tie for railway rails having its top at points inward of its ends centrally grooved in opposite directions, lugs integrally formed on the top of the tie, at the opposite sides of the grooves but having their confronting edges partly overlying the grooves, said lugs having their upper faces, from points adjacent their inner edges, beveled downwardly, a cushioning plate received between the spaced pair of lugs, for the reception of the base flanges of rails thereon, clamps comprising plates designed to be seated on the said beveled faces of the 60 lugs, said clamps having their under faces beveled in opposite directions for contacting respectively with the base flanges of the rails and the said beveled faces of the lugs, headed bolts received in the openings of the ties 65 having their shanks passing between the lugs and through the clamps, nuts screwed on the bolts and locking means between the clamps and nuts.

In testimony whereof I affix my signature.

CHARLES D. CURRY.
